UNITED STATES PATENT OFFICE

EDWARD A. MORRIS, OF SACRAMENTO, CALIFORNIA

CERTIFICATE HOLDER

Application filed November 19, 1928. Serial No. 320,303.

This invention relates to holders for the registration certificates of motor vehicles, and particularly to one of that type which is adapted to be strapped about the steering post or column of the vehicle.

The present invention also relates particularly to structures of the general form shown in my co-pending application for patent, Serial No. 317,218, filed Nov. 5, 1928. The principal object of this present invention is to provide a structure for the purpose which is intended to be constructed of a cheaper grade of material than the former and which is easier and cheaper to manufacture and assemble; while retaining the desired neatness of appearance and having ample strength for its purpose.

These objects I accomplish by means of such structure and relative arrangement of parts as will fully appear by a perusal of the following specification and claims.

In the drawings similar characters of reference indicate corresponding parts in the several views:

Fig. 1 is a front view of the complete certificate holder.

Fig. 2 is a perspective view of the blank from which the body of the holder is formed.

Fig. 3 is a similar back view after the stiffening rods and celluloid sheet have been placed but before folding over the various flaps.

Fig. 4 is a perspective front view of the parts shown in Fig. 3 after folding.

Fig. 5 is an enlarged fragmentary cross section taken on the line 5—5 of Fig. 1.

Fig. 6 is a perspective view of a modified form of blank.

Fig. 7 is a similar back view of the holder as formed from such blank.

Referring now more particularly to the characters of reference on the drawings, and particularly at present to Figs. 1 to 5, the body of the certificate holder is formed as a sheet of heavy paper of suitable color and of preferably ornamental surface design. This sheet is stamped out to form a rectangular frame 1 outlining a rectangular opening 2, and side flaps 3 shorter than the frame and projecting from the sides

thereof in symmetrical relation to the top and bottom edges of said frame. In the plane of the junction of the flaps with the side edges of the frame the body is provided with longitudinal slots 4, the top and bottom edges of which are slit outwardly into the flaps a short distance, as shown at 5, so as to form additional narrow flaps 6. The inner side edges of the frame are slit laterally a short distance as shown at 7, these slits being continuations of the top and bottom edges of the opening 2.

After the blank is thus formed a sheet 8 of celluloid or the like is mounted in connection with the frame. This sheet is the same width as the distance between the ends of the opposed slits 5 and its height is the same as that of the flaps 3. This sheet is placed so that the top and bottom portions lie on the outside of the frame, while the major portion of the length of the sides is inside the frame, as shown in Fig. 3.

This can be done by reason of the slits 7 and the flexible nature of the body material, which enables the frame about the opening to be easily deflected so that a part may be positioned on one side of the celluloid and a part on the other without danger of excessive bending or damaging of the material in any way. The top and bottom portions of the frame are then bent outwardly and over the ends of the celluloid in the form of protecting and retaining flanges 9, as shown in Fig. 4. By means of this particular mounting of the celluloid therefore it is held from slipping in any direction, and also against movement inwardly or out of the frame.

Rigid wire rods 10 the same height as the side flaps 3 are placed under the flaps 6, and the flaps 3 are then folded over onto the back of the body. This operation causes the flaps 6 to be folded into the slots 4 and about the rods, so that the latter are mounted in substantially hinge-like relation with the parts and are prevented from easy displacement during the subsequent handling of the holder incident to the further assembling operations.

U-shaped metal moldings 11 are then

placed about the flaps and frame at the folds thereof, said moldings of course embracing the rods.

The moldings extend from the top to the bottom of the body when the flaps 9 are folded over so that they also engage the ends of said flaps. The sides of the moldings are then pressed together so as to pinch and closely surround the rods as shown in Fig. 5. These moldings maintain the body rigid in one direction, while holding the wires against displacement; the latter preventing any pulling strain placed on the opposite sides of the body from tending to tear the same apart across the narrow connections between the ends and sides of the frame.

The area of the body between the flaps and the top and bottom is of sufficient size to receive a standard registration certificate, the data on which is of course displayed through the celluloid covered window. The flaps 3 protect the back of the certificate from contact with the steering column and also hold said certificate against undesired displacement in the event the holder is removed at any time. To secure the holder about a steering post a cord 12 or the like is slidably engaged with holes drilled through the moldings and adjacent thicknesses of material after the various parts have been assembled. If it is desired, however, to mount the holder against a flat surface the cord may be removed and the holes in the moldings used to receive tacks or screws.

In the form of the device shown in Figs. 6 and 7, the main form and structure is the same as that above described. In other words, the blank is formed with the frame 1^a, the main side flaps 3^a, and the end projections on the frame to form the outwardly bent end flaps 9^a to overlap the top and bottom ends of the celluloid sheet 8^a.

The frame at the top and bottom however instead of extending straight across along its inner edges, is slit from such edges to adjacent the bend of the flaps 9^a, some distance from and parallel to the plane of bending 50 of the side flaps 3^a, and the material of the blank is extended into the frame-opening some distance to form inner top and bottom flaps 13. These flaps allow the certificate to be placed thereunder so that such certificate will be engaged at its ends between such flaps and the celluloid; the side flaps being of course folded or superimposed over the end flaps.

It will be obvious that these added flaps do not use any additional material, since they are formed from the material cut from the frame-opening, which was previously wasted.

From the foregoing description it will be readily seen that I have produced such a

device as substantially fulfills the objects of the invention as set forth herein.

While this specification sets forth in detail the present and preferred construction of the device, still in practice such deviations from such detail may be resorted to as do not form a departure from the spirit of the invention; as defined by the appended claims.

Having thus described my invention what I claim as new and useful and desire to secure by Letters Patent is:

1. A certificate holder including a body consisting of a frame surrounding an opening, and side flaps formed with the frame to fold over against the back of the frame; metal mouldings along the sides of the outer faces of the frame and engaging the outer faces of the frame and flaps adjacent the junction thereof, and means for securing the holder about a steering post, mounted in direct connection with the mouldings.

2. A certificate holder including a body consisting of a frame surrounding an opening, and side flaps formed with the frame to fold over against the back of the frame; metal reinforcing rods arranged to be disposed in the folds between the flaps and frame, and means formed with the body for preventing lateral shifting of the rods when the flaps are folded over.

3. A certificate holder including a frame of flexible material to surround an opening, the frame having short slits cut therein extending laterally from the opening at the top and bottom thereof, a sheet of transparent material to cover the opening and projecting at its sides into the slits whereby the frame material will lie partly on one side of the sheet and partly on the other, and the sheet will be held against lateral shifting, and flaps formed along the frame at top and bottom to bend over and enclose the end portions of the sheet to prevent the sheet from longitudinal shifting movement.

4. A structure as in claim 3, with means engaging the ends of the flaps to hold them in folded position.

In testimony whereof I affix my signature.

EDWARD A. MORRIS.
